UNITED STATES PATENT OFFICE.

HERMAN A. DAAKE, OF ROCHESTER, INDIANA.

DESIGN FOR A STATUETTE.

Application filed November 30, 1927. Serial No. 24,348. Term of patent 7 years.

To all whom it may concern:

Be it known that I, HERMAN A. DAAKE, a citizen of the United States, residing at Rochester, in the county of Fulton, State of Indiana, have invented certain new, original, and ornamental Design for a Statuette, of which the following is a description, reference being had to the accompanying drawing, forming part thereof.

The dominant feature of the design is the employment of children's figures in expressive attitudes in conjunction with a railway crossing sign in the background.

I claim:

The ornamental design for a statuette, substantially as shown and described.

In testimony whereof, I affix my signature.

HERMAN A. DAAKE.
